SAFETY-RAZOR.

1,075,976.

Specification of Letters Patent.

Patented Oct. 14, 1913.

Application filed March 10, 1913. Serial No. 752,175.

To all whom it may concern:

Be it known that I, ERNEST N. HUMPHREY, a citizen of the United States, residing at New Britain, county of Hartford, State of Connecticut, have invented certain new and useful Improvements in Safety-Razors, of which the following is a full, clear, and exact description.

This invention relates to so called "safety razors," and is designed to provide a simple and efficient device of this character wherein provision is made for the effective clamping of the razor blade in adjusted position and, wherein the structure permits 15 of substantial economies in manufacture without detracting from the utility or appearance of the device. These and other advantages will be fully described in the following detailed specification taken in connection with the accompanying drawings 20 forming part thereof and illustrating a preferable part of the invention.

In these drawings: Figure 1 is a view in rear elevation of a safety razor constructed 25 in accordance with the present invention. Fig. 2 is a view in end elevation of the razor shown in Fig. 1. Fig. 3 is a vertical section taken on the line 3—3 of Fig. 1. Fig. 4 is a view in elevation of the rear end 30 of the blade clamping lever.

Referring to the drawings by numerals, 1 indicates the handle or stem of the device to the upper end of which is fixedly secured a blade supporting base or plate 2 having its forward edge slotted and depressed to form a guard member 3, and having elevated stop shoulders 4 at the extremities of the guard edge to limit the extreme forward position of the cutting 40 edge of the razor blade adapted to be supported by the base 2. The forward edge of this base inclines downwardly at a slight angle as is usual in razors of this type, and at its rear edge adjacent the opposite ends 45 thereof the base is provided with integral upstanding lugs 5, and with integral ears 6 extending upwardly from its side edges adjacent their rear ends, these ears being in alignment and having therein aligned apertures 7. The razor blade 8 is preferably of the non-flexible wafer type and is seated on the upper base of its supporting face 2. The lugs 5 serve to retain the blade on the base with its forward cutting edge 55 properly positioned relative to the guard 3,

whose stop shoulders 4 are positioned to lie at a point forward of the cutting edge of the blade and to act as stops preventing said blade from projecting forwardly to a point too near the edge of the guard 3. 60

In order to securely hold the blade 8 on its supporting base when properly positioned thereon, I provide clamping means which I regard as of a particularly advantageous construction. This means is in the form of a bell crank plate acting as a cam lever and having a long arm or main body portion 9 provided with outwardly offset ends 9^a and having a short arm 10 at an angle thereto. This short arm 10 has extending from its side edges pivot studs 11 which are seated through the aligned apertures 7 in the ear 6 of the supporting plate 2. The edge 12 of the short arm of the lever has a cam action against the upper 70 face of the blade 8 resting on the plate 2, the components of the lever being figured to bring this cam edge 12 in strong frictional engagement with the upper face of the razor blade. The main body portion 9 of this cam lever extends longitudinally of the supporting plate 2 and covers the greater portion of the razor blade. The ends 9^a of this cam plate project beyond the edges of the supporting plate 2 of the 75 razor blade, and afford a finger grip whereby the cam plate may be manipulated. The clamping edge 12 of this plate extends substantially the entire length of the supporting plate 2 and of the razor blade, so 80 that the blade is effectively gripped at all 85 points.

In order to secure an efficient frictional grip without making the clamping and unclamping action unnecessarily hard, I prefer 95 to make the clamping cam edge of the cam plate resilient, so that it may effectively clamp blades of varying thickness within reasonable limits and will enable the clamping and unclamping action to be smoothly and easily 100 performed owing to the spring of the clamping edge. This I preferably secure by forming the short arm 10 with the cam plate or lever with a slot 13 extending longitudinally thereof for the greater portion of its length 105 and so destroying the rigidity of the arm that its base has a spring action. This action is productive of another advantage, in that when the cam plate is moved downwardly to bring its cam edge 12 in clamp- 110

ing engagement with the razor blade, the tension under which the cam edge is placed imparts a spring clamping action to the forward edge of the arm 9 of the cam plate and 5 tensions the forward edge of this arm against the forward edge of the razor blade, thereby clamping the same on its seat at two points—*i. e.*, adjacent its forward and rear end. While I deem it preferable to provide 10 this resilient clamping edge by forming a slot longitudinally thereof, inasmuch as its entire cam plate may be stamped from sheet metal and the slot punched therein during the stamping operation, it will nevertheless, 15 be obvious that the same result can be secured by simply constructing the cam edge of the lever of resilient material which will effect the results named.

The clamping cam lever and base plate 20 may be both readily constructed from sheet metal as indeed may the handle if so desired. The entire device may be very economically manufactured both from the standpoint of material and labor.

25 It is hardly necessary to describe the operation as it will be obvious with the parts in position shown in Fig. 2 of the drawings, that by grasping the finger pieces 9^a of the clamping lever, the forward end of the same 30 may be moved upwardly against the tensioned frictional engagement of the cam edge 12 and swung clear of the razor blade which may be removed for cleansing or for the insertion of a new blade. In order to clamp 35 the blade on its seat after it has been properly positioned thereon, it is only necessary to move the forward end of the clamping lever downwardly. This movement of the lever brings its rear cam edge 12 into com- 40 paratively strong frictional engagement with the upper face of the razor blade, the rear arm 10 of the cam plate being somewhat resilient because of its slot 13, serving to transmit tension from the frictionally en- 45 gaged rear edge of the cam plate to its forward edge so as to hold this forward edge tensioned against the upper face of the razor blade against its forward edge, thereby hold- 50 ing the razor blade at two points and substantially the entire length of the blade.

While I have herein described and illustrated a preferable embodiment of the invention, it will, of course, be apparent that various structural modifications are possible within the spirit of the invention and the 55 scope of the appended claims.

What I claim therefore and desire to secure by Letters Patent is:

1. In a safety razor, a handle portion, a blade supporting base rigidly connected thereto and provided with a forward guard edge, and an angular clamping plate extending longitudinally of said base and comprising a long arm and a relatively short resilient cam arm having a longitudinal slot 60 therein, said clamping plate being pivotally mounted at its sides and intermediate its ends above said base and being positioned and arranged to frictionally engage the rear edge of its cam arm with the upper face of a 70 razor blade adjacent its rear end to thereby tension said rear arm whereby the forward edge of said long arm is held tensioned against said razor blade adjacent its forward edge. 75

2. In a safety razor, a handle portion, a blade supporting base rigidly connected thereto and provided with a forward guard edge and with stop shoulders adjacent thereto, oppositely disposed and alined lugs 80 extending upwardly from the sides of said base intermediate its forward and rear edges, an angular clamping plate extending longitudinally of said base and comprising a long arm and a relatively short resilient cam arm 85 having a slot extending longitudinally thereof, said clamping plate being pivotally mounted between said lugs and above said base intermediate its forward and rear edges and being positioned and arranged to frictionally engage the rear edge of its cam arm with the upper face of a razor blade adjacent its rear end to thereby tension said rear arm whereby the forward edge of said long arm is held tensioned against said razor 95 blade adjacent its forward edge. 90

ERNEST N. HUMPHREY.
